[57] CLAIM

The ornamental design for a fluid sensor mounting track, as shown and described.

DESCRIPTION

FIG. 1 is a front elevational view of a fluid sensor mounting track embodying the invention, which is identical to the rear elevational view thereof;

FIG. 2 is a right side elevational view thereof, which is identical to the left side elevational view thereof;

FIG. 3 is a top plan view thereof;

FIG. 4 is a bottom plan view thereof; and,

FIG. 5 is a bottom, front perspective view thereof.

FIG. 1

FIG. 2

FIG. 5

FIG. 3

FIG. 4
